FISHING LURE OR THE LIKE

Jack E. Davis, Georgetown, Fla., assignor to Victor Comptometer Corporation, Chicago, Ill.

Filed May 1, 1972, Ser. No. 249,483

Term of patent 14 years

Int. Cl. D22—05

U.S. Cl. D22—27

FIG. 1 is a perspective view of a fishing lure or the like embodying my new design;
FIG. 2 is a top view thereof;
FIG. 3 is a front end view thereof;
FIG. 4 is a side elevational view thereof;
FIG. 5 is a rear end view thereof;
FIG. 6 is a bottom view thereof; and
FIG. 7 is another side view thereof opposite the view of FIG. 4.
The hooks have been omitted in FIGS. 2 and 7 for convenience of illustration.

I claim:
The ornamental design for a fishing lure or the like, as shown and described.
